United States Patent

Des. 236,734
Patented Sept. 9, 1975

236,734

TELEPHONE HOUSING

Gerald Ray Daum, Dallas, Tex., assignor to Texas
Instruments Incorporated, Dallas, Tex.

Filed Nov. 4, 1974, Ser. No. 520,683

Term of patent 14 years

Int. Cl. D14—03

U.S. Cl. D26—14 A

Fig. 1

Fig. 2

Fig. 3

Fig. 4

Fig. 5

FIG. 1 is a view in perspective of a telephone housing embodying my new design;

FIG. 2 is a left side elevation of the telephone housing;

FIG. 3 is another view in perspective with the hand set removed;

FIG. 4 is a top plan view thereof; and

FIG. 5 is a rear elevation thereof.

I claim:

The ornamental design for a telephone housing, substantially as shown.
